[57] ABSTRACT

The invention prevents the effects of transversal listing moments on the hull of a hydrofoil craft by providing at least one hinged strut between the hull and a wing as well as control and sensing means. The sensing means sense list causing forces and/or list causing flow and the control means tilt the respective hinged strut in response to the sensing means instantaneously into such an angular position that the listing moments are eliminated even before they can become effective on the hull.

DEVICE FOR HYDROFOIL CRAFTS SUITABLE TO REMOVE FROM THE BEGINNING THE TRANSVERSAL LISTING MOMENTS

BACKGROUND OF THE INVENTION

The present invention relates to a list preventing device, more specifically, to such device for use in hydrofoil crafts.

It is well known that hydrofoil crafts with completely immersed wings obtain their navigational stability transversally and longitudinally by gyroscopic stabilization means which control, through electronic-hydraulic actuation elements, the flaps of the supporting wings. The hull of such crafts is connected to its immersed wings through vertical struts which are rigidly attached to the hull thus forming an integral part of the hull. These struts are the main source of transversal listing effects to which the hull is subjected. In fact, the presence, e.g., of a horizontal orbital motion causes on the immersed vertical planes of said struts a reducing F which, multiplied by the vertical distance Z between the center of gravity G of the hull and the plane in which said force F is effective, results in a transversal dynamic listing moment which must be balanced completely by the straightening moment. The same balancing is required with regard to static listing moments.

In a conventional geometrical form as shown in FIG. 1, the vertical struts are transversally or laterally arranged one on each side of the hull, and the distance B between the struts defines with forces ΔP the straightening moment MR whereby ΔP is the difference is lifting caused by the opposite action of the flaps of the supporting wings; that is $MR = \Delta PB$. The flying height H , that is the distance between the bottom of the hull and the water surface, to which Z is proportional, defines the degree of sea roughness which the hydrofoil is able to overcome and thus its efficiency degree with respect to the wave height.

Therefore, it is an advantage to increase said flying height H because this increases the operational efficiency of the craft. However, efforts to increase the flying height of presently known crafts, which height is rather limited, have resulted in increased listing moments which depend both on Z and F , the latter when caused by orbital motions increasing together with the increase of the flying height H or the height of the wave to be passed over. Consequently, for lifting the hydrofoil crafts even more above the water surface, it is necessary to increase the straightening moment MR comprising a constant factor B and a variable factor ΔP . Such increasing of the straightening moment has at present reached its last hydrodynamically feasible possibilities. Therefore, a significant increase in the flying height cannot be attained by the systems presently used. Accordingly, prior art hydrofoil crafts must bear the listing effects before they can be balanced whereby a rather hard navigation and substantial stresses of the boat structure result.

OBJECTS OF THE INVENTION

In view of the foregoing the invention aims at achieving the following objects:

to remove the above drawbacks;

to prevent the effect of or to remove transversal listing moments, especially in hydrofoil crafts due to a horizontal orbital motion of waves;

to increase the flying height by increasing the length of the struts and consequently the sea worthiness;

to prevent or remove such listing moments from the very beginning, that is, before these moments become effective on the hull;

to prevent or remove dynamic and/or static listing moments produced by the transversal component of the horizontal orbital motion of the waves;

to assure a substantially higher flying height of hydrofoil crafts without the need for increasing the balancing or straightening moments presently available in known hydrofoil crafts;

to provide a much more comfortable ride and smoothness of navigation even where the flying height merely corresponds to presently available flying heights;

to substantially increase the navigational stability of hydrofoil crafts in the longitudinal as well as in the transversal direction relative to the craft;

to increase the efficiency and operability of hydrofoil crafts so that the steering becomes easier;

to reduce the stresses to which hydrofoil crafts are subjected while in operation on transversally effective rough seas;

to provide movable struts or fixed struts with movable flaps on the trailing edge of the struts for the wings of hydrofoil crafts regardless whether the wings are fully or partly immersed, and suitable as bow and/or stern struts;

to provide means for controlling the movement of movable struts or of movable strut flaps in hydrofoil crafts in response to force capable of causing listing moments.

SUMMARY OF THE INVENTION

The list preventing device according to the invention comprises one or more tiltable struts which are hinged to the hull to be tilted about a vertical axis, and control

means for the tiltable struts, as well as sensing means for sensing any forces and/or flow which may cause tilting moments. The control means are operatively connected to the sensing means and to the respective strut for instantaneously tilting the strut into an angular position

which corresponds to the instantaneous angle included between the forward direction of motion of the craft and a resultant of a forward and lateral or transversal speed component whereby any operative disadvantages and restrictions are removed because the various transversal dynamic and/or static listing moments are immediately removed, that is before the hull receives them. Therefore, much higher flying heights are obtained with the same straightening moments present in known hydrofoil crafts. Further, a considerably better comfort and smoothness of navigation is achieved at flying heights comparable to presently achievable flying heights.

The sensing means are capable of ascertaining a physical quantity depending on the transversal speed of the liquid surrounding the supporting vertical struts of the hydrofoil crafts due to the horizontal orbital motion of the waves. The control means which may be of any kind are suitable for controlling, for example by means of a servomechanism said angular strut position.

Said sensing means may comprise mechanical, electric, hydraulic and pneumatic elements or other suitable members of any kind arranged on the hull or on a

suitable immersed portion of the strut and able to ascertain the amount and direction of the transversal flow or one of its effects. For example, the sensing means could measure the mechanical stresses produced by an exciting force or depending on the transversal flow, or the pressure or any other function or effect of the transversal speed of said flow on the immersed struts.

The physical value representing for example speed, force, acceleration, displacement or the like and sensed in response to the transversal or lateral speed of the fluid flow is preferably transformed into any electric, electronic mechanical, hydraulic or displacing signal which may be conveniently amplified for controlling said servo-mechanism in a closed-loop circuit whereby to automatically adjust the instantaneous angular strut position either by rotating the axis of null lift of the vertical struts or by causing a suitable transversal variation in the lift thereof.

According to the invention there is further provided lift varying means comprising means for blowing of air or water along one or more of the supporting vertical struts, said blowing being directed transversally to the hull and having an intensity and direction depending on the intensity and direction of said transversal speed whereby the varying of the strut lift is controlled in such a way as to remove said disturbing force.

In another embodiment according to the invention at least one flap-type vertical aileron is suitably arranged on one or more of said struts supporting the hull. Said aileron is controlled so as to produce a lift variation for balancing the transversal force produced by said transversal speed of the flow.

Said sensing means comprise, for example, extensometers which may operate mechanically, pneumatically, or electrically on the strut or in the hull, to check any deformation of the carrying struts caused by said transversal speed of the fluid.

BRIEF DESCRIPTION OF THE DRAWINGS

In order that the invention may be clearly understood, it will now be described, by way of example, with reference to the accompanying drawings, wherein:

FIG. 1 shows the cross section of a hydrofoil craft raised to a height H above the water surface or horizontal X—X;

FIG. 2 shows a partial lateral view of said hydrofoil craft with a vertical strut hinged to the hull along an axis I—I;

FIG. 3 shows the strut as viewed in the direction III—III of FIG. 2 said strut being rockable or tilttable about the axis I—I;

FIG. 4 shows a diagram of the resultant speed $V + v$ of the water flow;

FIG. 5 illustrates a section along line V—V of FIG. 2;

FIGS. 6 and 7 show a vertical strut fixed on the hull, and provided with a hinged vertical flap; and

FIGS. 8 and 9 illustrate longitudinal side and top views respectively, of a hydrofoil craft with completely immersed wings;

FIG. 10 illustrates the actuating means of FIG. 5 as applied to the flap of FIG. 7;

FIG. 11 is a view similar to FIG. 6 wherein the flap has been replaced by fluid jet holes in the side walls of the strut;

FIG. 12 shows the actuating means of FIG. 5 for operating the fluid jets in FIG. 11.

DESCRIPTION OF A PREFERRED EMBODIMENT

If, as is diagrammatically shown in FIG. 1, the hull 1 is transversally inclined by an angle β relative to the horizontal X—X, the weight Q as expressed in percent of the displacement and which bears on the wing pair 3, resolves into forces F_1 and Q_1 .

Where the struts 2 are integrally or rigidly attached to the hull as in the prior art 1, the force F_1 will cause a moment $MS = F_1 Z$, wherein Z is the vertical distance between the horizontal plane extending through the center of gravity G of the craft and the horizontal plane in which a force F is effective on the strut 2; said force F being exerted on the surfaces of the struts mostly by horizontal, orbital motion of the waves. On the other hand, where the vertical strut 2 is hinged to the hull as shown in FIGS. 2 and 3 according to the invention,

namely in front of the thrust center and along an axis I—I, the strut 2 is free to rock about a hinge 4. As a result, the force F_1 will not generate any listing moment, but will translate laterally the hull 1 with a speed component (v). In fact, as shown in FIG. 4, the combination of the speed V of the longitudinal movement of the hydrofoil and the speed (v) of the lateral or side displacement of the hydrofoil will define a resultant $V + v$. A rather slant angle α is included between the

direction Y—Y of forward motion and the direction of said resultant. The strut 2 will position itself at such angle α relative to the forward movement direction Y—Y, whereby the effect of the force F_1 is cancelled. The foregoing considerations apply to any one of the

various transversal exciting forces, caused for example by any orbital horizontal side motions of the waves. That is, a flow with the speed (v), as in the first example, will cause a resultant $V + v$ and a corresponding angle α and the rocking strut will immediately assume

such tilted position that from the beginning any effect of such forces as F or F_1 is avoided and therefore the listing moments caused by said forces are also avoided.

It is however to be considered that the vertical strut 2, which is free to tilt about the hinge along the axis I—I, represents in its practical embodiment relative to the water flow a rocking system with its own mass, inertia and damping factor so as to alter the effects it receives from the flow speed (v), and thus the strut will assume

positions according to angles which do not necessarily correspond to said angle α , resulting due to components V and v. The vertical strut 2 may also position itself at an angle corresponding to the angle but not within suitable response times whereby the effects of forces F and F_1 are not cancelled completely but only a part or fraction thereof. The system as above described may be called an open-cycle system which is subject to disturbances and undesirable phase shifts of various kinds.

For example when one of the wings 3, as shown in FIG. 3, is subject to an accidental and non-symmetrically effective force T acting at a force arm N with respect to the direction Y—Y, there will be a disturbing moment T times N with respect to the hinge axis which will tend to tilt the strut 2 to an angle which is independent of the flow speed (v) or of such forces as F or F_1 , whereby a subsequent listing moment of the hull is caused.

In order to remove the above disadvantages, it has been found to be necessary to control the tilting angles of the struts 2 exclusively in response to the flow speed (v) or factors depending thereon, as for instance the force F or the dynamic pressure or even the direction of flow. According to the invention such control is obtained by ascertaining or directly sensing the force of the flow speed (v), or any one of its functions or effects, by any suitable apparatus. The control may also be in response to sensing the mechanical stress effects caused by the force F, which is a function of the flow speed (v), and transforming such stress effects into a control signal which is used to control any mechanical, hydraulic, electric, electronic, pneumatic or composite closed loop system, so as to cancel the effects of said excitation forces by positioning the strut 2 at suitable angles α corresponding to the null lift axis of the strut outline.

An embodiment of a closed loop system is shown, for example, in FIG. 5. The strut 2 is shown in section along the line V—V of FIG. 2. Due to an effect to the flow speed (v) the force F causes a flexion of the strut 2, whereby the strut 2 assumes a flexed position as indicated by the dash-dotted line in FIG. 5. Such a flexion may be mechanically substantial in its infinitesimal values Δf as indicated by the movement of the free upper end of a sheet or flat member 12 the lower end of which is integral with said strut so that the free upper end is freely displaceable in a transversal direction.

The infinitesimal movement values Δf control through a follower member 11'' a hydraulic pilot servo valve 11 which is attached to the strut 2. The servo valve 11 is connected through hydraulic conduits 11' to an actuating element such as a piston cylinder device 10 pivoted to the strut 2 as at 10'. The arrangement is such that the strut 2 is always tilted in a direction which tends to reduce Δf to zero and thus to close the servo valve and thereby the response cycle. Consequently, as soon as the force F tends to begin, its effect is immediately cancelled through an angular tilting of the strut 2 about the axis I—I.

Such angular tilting or rotation of the strut 2 by the piston cylinder device 10 will position the strut 2 at said angle α which, as stated, is equal to the angle resulting from the composition of flows V and v at the very moment considered. Stated differently, the instantaneous, tilted position of the strut will always correspond to the instantaneous angle necessary for proper compensation of any list moments.

The effect of the flow speed (v) may be ascertained or sensed even directly, for example by introducing a sensing means of any type into a suitable immersed portion of the strut 2 and transmitting the value or signal sensed to the above described control device or to any other similar control device.

The mechanical stresses generated by the force F, or the pressures caused by the flow speed (v) or any effect or function caused by the flow speed (v) on said strut 2 may be transformed from any movement due to compression or acceleration into a respective electric or electronic signal which, suitably amplified, constitutes the control function of a closed cycle automatic control circuit for tilting the strut 2 to the required angle.

The desired effect of cancelling the listing moments obtained by cancelling the force F or any function of the flow speed (v) will be obtained by controlling the

tilting angles of the strut 2 regardless where the hinging axis I—I is located relative to the strut. For example, the hinges 4 may be located anywhere along the chord axis of the strut or along the longitudinal front face of the strut 2 as shown in FIG. 2, or along axes parallel to the chord axis of the strut.

Thus, the hinge axis I—I may be located in front of said strut, thus, e.g., between the strut and the stern, or at the center of the strut, or at the rear edge of the strut, for example between the strut and the stern, or even laterally of the strut. Different examples for positioning the hinge axis are shown in FIGS. 2, 3 and 8. According to another embodiment, the compensation for the transversal listing moments is obtained by balancing the force F by means of vertical flaps 13, shown in FIGS. 6 and 7, or by blowing air, water or the like, or by using any device capable of performing a variation of the controlled lift. In such a case the strut 2 is formed as an integral part of the hull 1.

As described above, the exciting force F, acting on the immersed part of vertical strut means 2, FIG. 5, can by sensing means such as the flat member 12 be transduced into a displacement signal Δf , suitable to the control of a hydraulic pilot servo valve 11 for actuating the piston cylinder device 10. The control takes place through a follower member 11''. If cylinder 10, as seen in FIG. 10 is connected to flap 13 by a link 10' so as to rotate the flap 13 about its hinge axis 2b by an angle (β) in the same direction and proportional in amplitude to F, at the start of the signal Δf , a hydrodynamic force will develop in the immersed part of the vertical strut means, having a value $-F \times (\beta)$ opposite to F, which shall produce a force resulting on the vertical strut means $F_y = F - F(\beta)$ within the limits required to compensate the list.

Assuming $F\beta/F_y = n$, in which (n) has an arbitrary value, preferably between 2 and 6, and $F\beta/F = \text{const.}$, and $F = F_y + F(\beta)$ we have: $F(\beta) = nF_y$ and $F = F_y + nF_y = F_y(1+n)$ and therefore $F(\beta)/F = \text{const.} = nF_y/(1+n)F_y = n/(n+1)$ which is the percentage of force reduced by the lift control with the flap 13.

According to another lift control arrangement shown in FIGS. 11 and 12 a number of holes 1' and 1'' are provided in the two sides of vertical strut means 2 along a vertical line. These holes are suitably connected through ducts 2', 2'' and pipes 3', 3'' to the two outlets of a distribution valve 4'' to which the fluid under pressure flows through a duct 5. The valve 4'' is controlled by the cylinder 10 by means of a linkrod 4a so as to cause a fluid which can be either air or water under pressure to flow to holes 1' or 1'' in either direction and corresponding in sense and being proportional to the intensity of signal Δf representing the force F. When in all the holes of one side of the vertical strut fluid sprays are formed, the lift of the immersed part of said vertical strut is altered so as to develop a $-F(\beta)$ force opposite to F as in the previous case with the flap.

The above device may be generally used on any hydrofoil craft having completely immersed wings or comprising a combination of completely immersed and/or partly immersed wings.

Further the hull may be provided with one or more or all struts controlled according to the invention by a closed cycle system or a composite arrangement.

FIGS. 8 and 9 show for example, a hydrofoil craft provided with two forward struts 14 and 16 which are hinged and controlled as described. A simple vertical strut 15 which is not tiltable is provided at the stern where it may be arranged to comprise a zed-type transmission for a propeller or the feeding conduits of a hydrojet. Neither the transmission for driving propeller nor the hydrojet for propelling the craft are part of the invention.

Assuming that said forward controlled hinged struts bear 60 percent of the total displacement, the hydrofoil craft will have to be provided with a known transversal stabilization system for balancing the listing moments caused by the vertical and horizontal orbital motion of the waves on a fixed stern strut or struts. Consequently, the hydrofoil craft will be able to rise 60 percent higher than present hydrofoil crafts although only the same straightening moment is applied.

If in the device of the present invention it is assumed that 2 is the minimum value of n , the result is:

$$F\beta = n \cdot F / (n+1) = (2/3) \cdot F \cong 67 \cdot F / 100$$

i.e., 67 percent of the listing forces due to horizontal orbital movements acting upon controlled vertical strut means are eliminated. For instance, supposing to control the lift only at the two fore vertical strut means of the hydrofoil and that said strut means' dimensions are proportional to the weight lying on the wings, for instance 60 percent of the weight on the fore wings, the resulting force of the whole shall be

$$F_y = (33/100) \cdot (60/100) \cdot F + (40/100) F \cong (60/100) F$$

in which F is the total force acting on the immersed part of the three vertical strut means. Therefore for the same listing moment (M_s) due to the horizontal orbital movements we have:

$$M_s = F \cdot Z = F_y \cdot Z \quad \text{where}$$

$$Z_y = F / F_y \cdot Z = 100/60 \cdot Z = 1.67 \cdot Z$$

and consequently H is proportional to Z : $1.67 \cdot H$, that is to say H_y can be 67 percent higher than H .

Hence, if the lift variation is controlled on all three vertical strut means, for the same 67 percent reduction coefficient the result is:

$$F\beta = 67/100 F \quad \text{and}$$

$$F_y = F - F\beta = F - 67/100 F = 33/100 F \quad \text{and}$$

$$Z_y = 100/33 Z = 3 \cdot Z;$$

where $H_y = 3 \cdot H$.

The important advance in the art achieved by eliminating the effects of such forces as F , is seen in the better navigation and comfort as well as in lower stresses for the structure of the craft at flight heights corresponding to those of conventional crafts as well as at higher flight heights whereby higher waves are better overcome.

Further, since the present invention requires lower straightening moments for reducing the excitations caused by the vertical orbital motions, the distance B between the struts shown in FIG. 1 may be reduced to the lowest possible distance. For example, when only one controlled tilting strut is arranged at one half the

hull length said excitations will be nearly cancelled. It is also an important advantage of the invention that the possibility of reducing B to a desired small value, allows one to construct hulls with the most suitable ratio between the length and the width for hydrofoil crafts employing the present invention. On the other hand, in order to increase the straightening moment in conventional hydrofoil boats, B must be increased thereby reducing the ratio between the length and width of the hull. The reducing of this ratio unfavorably influences the features of the hydrofoil craft itself. The invention has overcome this drawback in a surprisingly simple manner.

It is to be understood that the invention is not limited to the examples shown. It is intended to cover all modifications and equivalents within the scope of the appended claims.

What I claim is:

1. In a list preventing device for water crafts having a hull, hydrofoil means and strut means for connecting the hydrofoil means to the hull, the improvement comprising sensing means located for sensing a physical quantity produced by horizontal orbital motion of a wave which is effective transversally relative to the longitudinal hull axis, control means operatively connected to said sensing means, and strut actuating means operatively connected to said control means, whereby the actuating means are automatically controlled in response to and in proportion to the instantaneous value and direction of said physical quantity for eliminating from the beginning even before it can affect the hull, any effect of said physical quantity by virtual rotation of the null lift axis of the vertical strut means.

2. The list preventing device according to claim 1, further comprising means for hinging said strut means to said hull, and comprising means for hinging said strut means to said hull, and means for connecting said actuating means to said hinged strut means.

3. The list preventing device according to claim 1, wherein said strut means have a trailing edge said device further comprising flap means forming part of said trailing edge of said strut means, hinge means for hinging the flap means to the respective strut means, and means for connecting the actuating means to said hinged flap means.

4. The list preventing device according to claim 3, wherein the vertical height of the flap means corresponds substantially to that of the length of the vertical strut means below said hull.

5. The list preventing device according to claim 1, wherein said sensing means comprise an elongated flat member located inside said strut means, said flat member having a lower end rigidly connected to said strut means and a freely movable upper end for indicating any flexion of the strut means under the effect of said physical quantity, said sensing means further comprising a follower position for cooperation with the upper end of the flat member and connected to said control means for operating the control means in response to the instantaneously sensed value and direction of said physical quantity.

6. The list preventing device according to claim 2, wherein said control means is a hydraulic servo-valve connected to said actuating means.

7. The list preventing device according to claim 6, wherein said actuating means comprise a piston cylinder arrangement, said device further comprising hydraulic conduit means for interconnecting said piston cylinder arrangement and said hydraulic servo-valve to form a closed loop automatic follower circuit including said sensing means.

8. The list preventing device according to claim 1, wherein said actuating means comprise jet means for

varying the lift of said struts, said jet means being positioned for directing a fluid stream along said strut means and transversely relative to the hull, said jet means being operatively connected to said control means, for controlling the intensity and direction of said fluid stream in response to said physical quantity for removing the effects of said quantity.
